Lawrence M. Oakley Inventor
By his Attorneys
Emery Booth, Farney & Whittemore,

UNITED STATES PATENT OFFICE

LAURENCE M. OAKLEY, OF TRENTON, NEW JERSEY, ASSIGNOR TO ESSEX RUBBER COMPANY, OF TRENTON, NEW JERSEY, A CORPORATION OF NEW JERSEY

DESIGN FOR A SHOE HEEL

Application filed January 6, 1931. Serial No. 38,208. Term of patent 14 years.

To all whom it may concern:

Be it known that I, LAURENCE M. OAKLEY, a citizen of the United States, residing at Trenton, in the county of Mercer and State of New Jersey, have invented a new, original, and ornamental Design for a Shoe Heel of which the following is a specification, reference being had to the accompanying drawing, forming part thereof.

In the drawings,

Fig. 1 is a bottom plan of a shoe heel showing my new design, and

Fig. 2 is a section on the line 2—2 of Fig. 1.

The tread surface of the heel is divided by a narrow raised strip of rubber into two

distinct surface portions of contracting appearance, one of which is unornamented except as described below, and the other of which is ornamented with an interlacing network of ridges. Surrounding the nail receiving holes, which are arranged in the usual manner around the periphery of the heel, in ornamented and unornamented surfaces alike, are polygonal studs, each having a cup-shaped depression in which the hole is centrally located.

I claim:

The ornamental design for a shoe heel as shown and described.

LAURENCE M. OAKLEY.
